Attorneys

UNITED STATES PATENT OFFICE

THOMAS J. HOWLAND, OF LONG BRANCH, NEW JERSEY

BATHING CAP

Application filed December 2, 1929. Serial No. 411,102.

This invention relates to bathing caps and particularly to a bathing cap provided with means for pocketing the ears, whereby they will be relieved of the direct pressure of the bathing cap and effectively sealed against the entry of water.

Various forms of bathing caps have heretofore been proposed which are intended, in one form or another, to pocket the ears and seal them against the entry of water, but none of them have proven entirely satisfactory in use. According to one proposal the bathing cap is provided with openings opposite the ears, and the periphery of the openings is provided with ribs which project outwardly from the main portion of the cap and encircle the ears. The ribs generally conform to the shape of the ears and are of substantial thickness and of sufficient height to prevent a cover from pressing against the ear. Such a construction forms a pocket which effectively relieves the ears from pressure, but the ribs do not form a sufficiently tight seal with the head to keep out water under adverse conditions.

According to my invention the bathing cap is provided with ear pockets formed by ribs encircling ear openings in the cap, but special means are provided adjacent the edges of the openings for forming an effective seal with the head of the wearer, such means preferably consisting of cups or air pockets such as used in the bathing cap disclosed in my Patent No. 1,746,477, granted Feb. 11, 1930.

The invention will be further described in connection with the accompanying drawings, in which

Figure 1 is a side elevation of the bathing cap;

Fig. 2 is a cross section on line 2--2 of Fig. 1, and

Fig. 3 is an inside face view of a portion of the bathing cap showing the means adjacent the ear pockets for sealing them against the entry of water.

Referring to the drawing, the numeral 10 designates a bathing cap formed of elastic material and generally conforming to the contour of the head. The edge of the cap 10 is preferably reinforced by a member 11, the

inner side of which may be smooth or provided with ribs forming cups or air pockets as described in my aforesaid patent.

The cap is provided on opposite sides with the ear receiving openings 12 which generally conform to the shape of the ears. The periphery of these openings 12 are preferably formed with outwardly projecting ribs 13 which are of sufficient thickness to prevent them from collapsing. The ribs 13, together with a cover 14 which covers their outer edges, form a pocket for the ears. The ribs 13 are made of sufficient height so that the cover 14 is prevented from pressing against the ears.

To more effectively seal the ear pockets against the entry of water, the inner edges of the ribs 13 are provided with cups or air pockets 14 preferably formed by crossed ribs 15 which, under the influence of the elastic material, bear against the head of the wearer and form a series of vacuum cups encircling the ear. These vacuum cups increase the adhesion between the periphery of the ear pockets and the head and form a watertight seal which will not be broken even under the most adverse conditions.

The cups or air pockets 14 are shown as being of diamond shape, but it is to be understood that cups of other shapes may be used and will just as effectively seal the pockets against the entry of water; for example, the cups may be square, oval, round or any other shape.

Although the cups or air pockets 14 will be found sufficient to maintain a watertight seal around the ears of most persons, a chin strap 16 is preferably provided as the hollow or depression where the jaw joins the neck is very pronounced on some persons, and with those persons the chin strap 16 will be found helpful in causing the cups or air pockets in the lower edge of the inside of the ear pockets to maintain a watertight contact with the skin of the wearer.

While the invention has been particularly described in connection with cups or air pockets for forming a watertight seal around the edges of the ear pockets, the invention is not limited to this particular means except as it

is claimed specifically in the appended claims.

I claim:

1. A bathing cap comprising a main portion of elastic material having ear-receiving openings, portions covering the openings and forming ear pockets and means adjacent the edge of the openings and extending at least a part way therearound and also extending inwardly from the cap towards the head to 10 form with the head a watertight seal.
2. A bathing cap comprising a main portion of elastic material having ear-receiving openings, portions covering the openings and forming ear pockets and ribs adjacent the 15 edge of the openings and extending at least a part way therearound for forming a watertight seal with the head of the wearer.
3. A bathing cap comprising a main portion of elastic material having ear-receiving 20 openings, portions covering the openings and forming ear pockets and cups or air pockets adjacent the edge of the openings and extending at least a part way therearound for forming a watertight seal with the head of the 25 wearer.
4. A bathing cap comprising a main portion of elastic material having ear-receiving openings, portions covering the openings and forming ear pockets and crossed ribs forming 30 cups or air pockets adjacent the edge of the openings and extending at least a part way therearound for forming a watertight seal with the head of the wearer.
5. A bathing cap comprising a main portion of elastic material having ear-receiving 35 openings, outwardly extending ribs encircling the openings, covers connected to the projecting edges of the ribs and forming with said ribs ear-receiving pockets, and means 40 formed on the inner edges of said ribs and extending at least a part way around said openings for forming a watertight seal with the head.
6. A bathing cap comprising a main portion of elastic material having ear-receiving 45 openings, outwardly extending ribs encircling the openings, covers connected to the projecting edges of the ribs and forming with said ribs ear-receiving pockets and ribs forming 50 cups or air pockets on the inner edges of said ribs and extending at least a part way around said openings for forming a watertight seal with the head.

In testimony whereof I affix my signature.
THOMAS J. HOWLAND.
